CHAIR BACK

REISSUED

Application filed July 14, 1927. Serial No. 205,701.

This invention relates to improvements in chair backs, and is particularly directed to a chair back for use with a chair of the general type used by stenographers and others who desire a support for the small of the back.

In chairs as heretofore constructed, it is the usual practice to adjustably mount the forked arms or uprights at the back of the chair but the back pad or back member carried by these uprights does not accurately fit the back of the user and when the uprights are adjusted, the angularity of the back is altered in a manner to produce discomfort.

This invention is designed to overcome the defects noted above and objects of such invention are to provide a novel form of chair back which is so made that although the uprights may be adjusted, as required, that nevertheless, the chair back will automatically adjust itself to the exact needs of the user.

A further object of this invention is to provide a novel form of chair back which is pivotally carried on the upright or uprights and which automatically returns to an approximately vertical position when the operator leaves his seat, and which instantly adjusts itself to his exact requirements when the chair is again occupied.

Further objects are to provide a novel form of chair back in which contact with any bony portion of the body is wholly avoided and the chair back is so contoured and formed that it fits around the back of the user without binding against any portion of the back bone, but which furnishes the requisite support for the back at the small of the back, where it is most needed, and which although provided with a rigid frame, nevertheless is so padded and formed that a yielding cushion-like structure is attained.

Embodiments of the invention is shown in the accompanying drawings in which:

Figure 1 is a front elevation of the chair back;

Figure 2 is a sectional view on the line 2—2 of Figure 1;

Figure 3 is a sectional view on the line 3—3 of Figure 1;

Figure 4 is a view from the front of the 50 chair back with the cover and padding removed and with parts broken away;

Figure 5 is a sectional view on the line 5—5 of Figure 4;

Figure 6 is a sectional view on the line 6—6 of Figure 4;

Figure 7 is a side elevation of the upper portion of a chair equipped with the back;

Figure 8 is a front view of the upper portion of the chair with parts broken away; 60

Figure 9 is a view of a modified form of back showing the frame partly in section and the padding and associated flexible sheets removed;

Figure 10 is a sectional view through the 65 back;

Figure 11 is a fragmentary plan view of the attaching clip carried by the upright.

Referring to the drawings, particularly Figures 1 to 6, it will be seen that the chair back comprises a rigid frame formed of a pair of side members 1, a top 2, and a bottom member 3. It is to be noted particularly from Figure 2, that the bottom member is materially larger and heavier than the top member and that the side members 1 taper towards the bottom member in a gradual manner. This latter construction is shown most clearly in Figure 5, from which it will also be seen that the members are curved, 75 particularly the side members 1, so that they arch outwardly or forwardly, as shown.

It is to be noted also that the top and bottom members are inwardly curved, or in other words, are arched rearwardly; for example, 80 the bottom member 3 has been shown in Figure 6 to bring out this construction.

A pair of cross straps 4 and 5 of inelastic material is secured to the front face of the marginal frame members, just described, and 85

these inelastic strap members are covered by an inelastic member 6, positioned in front of the inelastic straps, as shown in Figure 4. These inelastic members are freely yielding and when in final position, as shown in Figures 2 and 3, they are bowed rearwardly a slight distance. This bowing is caused by the fibrous or other yielding packing 7, which is interposed between the cover 8 and the members 4, 5, and 6. The flexible cover 8 is wrapped about the margins of the frame and secured in place, as indicated in Figures 2 and 3. This flexible cover and the padding and the inelastic members 4, 5, and 6, cooperate to position the cover 8 substantially straight across, as measured along a horizontal line and shown in Figure 3, and slightly bulged, as measured along a vertical line and shown in Figure 2. The rearward bowing of the inelastic members 4, 5, and 6 prevents any further sagging of these members, as the component of their pull is forwardly and thus a further deflection of them is prevented. In other words, the padding is not interposed with the cover bowed very far outwardly and the back members straight, but is so positioned that the back members are bowed rearwardly and the cover is substantially straight except for a slight bowing as measured along a vertical line and described above.

It is to be noted particularly that the padding 7 or filling, extends between the marginal frame and the cover and gradually tapers outwardly or thins as the side edges of the marginal frame are approached, as is clearly shown in Figures 2 and 3. The thickest portion of the padding is located centrally where it is most needed.

It is to be noted particularly that the bottom member 3 arches upwardly adjacent its center, as indicated by the reference character 9 in Figure 4, so that the back is provided with an upwardly cut bottom edge and with downwardly extending corners. This form of the back is also shown in Figures 1 and 8, and it is to be noted that the construction is such that the corner portions extend a slight distance around the sides of the operator at the fleshy portion of his back and removed from the spinal column. At the spinal column the back is cut upwardly, as described above, so as to avoid any cutting at this point. In addition to this, the padding interposed between the marginal frame and the cover guards against this undesirable effect.

The net result of this construction is that there is no uncomfortable cutting or binding of the back of the seat against the back of the user, but instead the back of the seat conforms accurately to the small of the back of the user.

The back of the seat, it will be noted from Figures 2 and 5, is provided with a pair of apertures 10 through its side portions 1 and 65 these apertures are located above the center

line of the back. In addition to this, the weight of the frame is greater adjacent its bottom portion. From these two conditions, it is apparent that the center of gravity of the seat is at a point spaced a material distance below the axis of the apertures 10. From Figures 7 and 8, it is readily seen that a pivot bar or rod 11 is passed through these apertures 10 and is carried by the uprights or upwardly extending arms 12, hereinafter described in greater detail. Thus, the back of the seat is pivoted above an axis spaced above its center of gravity and the back is consequently, a full floating back which freely adjusts itself to the exact requirements of the user and which always automatically returns to an approximately vertical position when the chair is not occupied, so that it is in a position adapted for instant use without any adjustment on the part of the operator.

Various means may be employed for supporting the end of the rod 11. In the form shown in Figure 8, a pair of knobs or sleeves 13 are screwed upon the threaded outer ends of the rod 11, it being noted that such threaded ends are reduced to provide shoulders 14 adjacent the edges of the back of the seat. Further, it is to be noted that a lock nut in the form of a washer 15 is screwed tightly against these shoulders and the sleeve of the bearing member 13 is screwed tightly against the lock nut. Thus, the spacing between the enlarged head of the sleeve or bearing member 13 and the lock nut 15 is fixed and this spacing is slightly greater than the thickness of the uprights 12. Thus, there can be no binding at this portion of the structure and the bearing members 13 freely turn within the apertured portions of the uprights 12. It is preferable to provide each headed portion of the bearing members 13 with a screw driver receiving slot, as shown in Figure 7.

The uprights 12 are adjustable and yieldingly held in any desired position relatively to the seat 16 in any usual or customary manner. The details of this construction have not been shown as it may be conventional.

Further, it is desirable to pivotally and yieldingly mount the seat upon the head 17 of the screw 18 in the customary manner.

It is to be noted however that the uprights 12 are arched rearwardly at the point indicated by the reference character 19 so as to accommodate portions of the user without any chance of binding against his body, so that the entire forward thrust against the body of the user is borne by the full floating completely padded back. Thus, users of widely differing builds or physiques are accommodated by this self-adjusting type of chair and the utmost comfort is attained.

Referring to the modified form of the invention shown in Figures 9, 10, and 11, it will be seen that the same type of frame as that previously described, may be employed with

a single upright 20. This single upright is positioned centrally of the back and is provided with an attaching clip 21 having in-turned tongues or faces 22 which are apertured for the reception of the screws 23 (see Figure 10).

Further, it is to be noted that the clip is provided with a pair of forwardly projecting apertured tongues 24 which receive the 10 horizontal pivot rod 25. This rod 25 may be either pivotally carried by the tongues 24 or else may be socketed within the bearing members 26 secured to the sides 27 of the chair back. It is to be noted that the upright 20 is curved inwardly (see Figure 10) to provide 15 room for the swinging of the bottom 28 of the frame for the back. The top 29 of the frame can swing over the upper end of the upright 20. It is apparent that by having the rod 20 rigidly carried by the tongues 24 that lateral 20 shifting of the back cannot occur. The members 26 are inset in apertures formed in the sides 27, as shown, and are provided with projecting feet through which screws or tacks 25 pass, as shown in Figure 10.

It will be seen that a full floating automatically adjusting back has been provided which is formed in a novel manner and which wholly avoids any possibility of cutting or 30 other discomfort to the user.

Although the invention has been described in considerable detail, such description is intended as illustrative rather than limiting as the invention may be variously embodied and 35 as the scope of such invention is to be determined as claimed.

We claim:

1. A back construction for a chair comprising a rigid marginal frame having a top, 40 side members, and an upwardly and rearwardly curved bottom member, said bottom member being larger than said top, said side members being tapered and being forwardly arched, an inelastic backing member secured 45 to said frame on its front face and being rearwardly bowed, a flexible front cover wrapped around the edges of said frame and secured thereto, and a yielding padding interposed between said backing member and said cover 50 and between said frame and said cover, said padding being thickest adjacent the center of the back and gradually thinning at the edges of said frame, the said cover being substantially straight along horizontal lines adjacent 55 its center and being slightly bowed forwardly along vertical lines.

2. In chair construction, a back comprising a rigid marginal frame having a top, side members and bottom member, said side members being tapered and forwardly arched, means for pivotally mounting the frame with its pivoted axis located above its center of gravity, an inelastic backing member secured to said frame on its front face and being rearwardly bowed, a flexible front cover wrapped 65

around the edges of said frame and secured thereto and a yielding padding interposed between said backing member and said cover and between said frame and said cover, said padding being thickest adjacent the center of the back and gradually thinning out the edges of said frame, the said cover being substantially straight along lines adjacent its center and being slightly bowed along vertical lines.

In testimony that we claim the foregoing 75 we have hereunto set our hands.

WALTER J. JOHNSON.
ARTHUR L. JOHNSON.
